UNITED STATES PATENT OFFICE.

IRA O. WRIGHT, OF BALTIMORE, MARYLAND.

DRAFT AND BUFFING GEAR FOR CARS.

1,106,531.

Specification of Letters Patent. Patented Aug. 11, 1914.

Continuation of application Serial No. 434,713, filed May 25, 1903. This application filed January 27, 1910. Serial No. 540,386.

To all whom it may concern:

Be it known that I, IRA O. WRIGHT, a citizen of the United States, residing at Baltimore city, State of Maryland, have invented certain new and useful Improvements in Draft and Buffing Gear for Cars, of which the following is a specification, this application being a continuation of my application No. 434,713, filed May 25, 1903.

10 The main object of my invention is the provision of a draft and buffing gear for cars wherein the strains and blows of buffing and drawing shall be transmitted to the central stringers or floor frame at a plurality of points or places, thus distributing the same over a large area of surface whereby rupture, bending and injury of the elements constituting the gear and frame will be prevented.

20 A further object is the provision of a gear which can easily be assembled and quickly repaired when necessary, and wherein draft links are substituted for the yoke.

The invention consists in certain novelties of construction and combinations and arrangement of parts as hereinafter set forth and claimed.

The accompanying drawing illustrates an example of the physical embodiment of the invention constructed according to one of the best modes I have so far devised for the practical application of the principle.

Figure 1 is a longitudinal section of Fig. 2. Fig. 2 is a top plan of the gear as a whole. Fig. 3 is a cross section of Fig. 2 on line $s-s$, the straps for supporting the follower blocks being omitted, as they are of a well known construction. Figs. 4 and 5, respectively, show a cheek plate and a draft link. Fig. 6 shows the filler block in section taken on line $x-x$, Fig. 2. Fig. 7 shows a relatively short key which may be used in lieu of the relatively long front key.

45 Referring to the several figures, the numeral 1 designates the center sills or stringers, in this instance of steel channel beams with their flanges turned outwardly; 2, the end sill; 3, the two cast metal cheek plates; 4, the rivets by which the cheek plates are secured to the webs of the channel beams; 5, a slot at the front end of each cheek plate for receiving and guiding the end of the key passed through the draw bar; 6, an open space in the rib partially surrounding

slot 5 to allow the passage of the ends of a short key when such key is used; 7, the front abutments for the front follower block or plate; 8, the rear abutments for the block or plate, said abutments consisting of vertical projecting ribs upon the face plates and integral therewith; 9, the recess within which the ends of the front follower block moves backwardly and forwardly; 10, the front abutments for the rear follower block or plate; 11, the rear abutments for the rear follower block or plate; 12, the recess between the two abutments within which the rear follower block or plate can move; 13, two perforated lugs or flanges at the bottom edge of each cheek plate; 14, two metallic straps or plates for supporting and holding the follower blocks or plates in their proper relative positions; 15, bolts passed through the holes in the lugs 13 and holes in the ends of the straps; 16, nuts on the bolts; 17, a metallic filler block, at the rear of the rear follower block, having flanges by which it is riveted to the webs of the channel beams, as shown; 18, a recess in the filler block to receive and guide a stem upon the rear follower block; 19, the rear follower block; 20, a stem on the block movable within the recess 18 of the filler block; 21, projecting lugs upon the face of the block which support the helical springs; 22, three projecting lugs or arms at each vertical edge of the block, the middle lugs at each edge being seated within the rear slots of the draft links; 23, the front follower block or plate constructed identically like the rear follower block 19 and having a stem 20 seated within a recess at the end of the draw bar, two lugs 21, and three lugs or arms 22, movable within the recess 9, the middle lugs or arms at each side being located within the middle slots of the draft links; 24, two helical springs supported between the follower blocks or plates; 25, the coupler and draw bar; 26, a horizontal slot adjacent the rear end of the draw bar; 27, a key inserted within the slot in the draw bar and movable therewith; 28, the draft links; 29, the front slot in each link, the same being approximately $1\frac{1}{2}$ " longer than the width of the ends of the key whereby the key can move rearwardly without imparting motion to the links in buffing; 30, the middle slot in each link which is about $1\frac{1}{3}$ " longer than the width of the middle lug or arm 22 at 110

the side of the front follower block or plate, whereby in drawing the links can move forwardly $1\frac{3}{4}$ " over the lugs before coming in contact with the said lugs or arms; and 31 5 is the rear slot in each link, and within which slots are loosely seated the middle lugs at the sides or edges of the rear follower block or plate.

The several parts and elements being arranged in the relative normal positions shown by the figures of the drawing, the *modus operandi* is as follows: In drawing, the draw bar moves forwardly, carrying with it the key, the two links and rear follower block or plate and compressing the springs, the middle slots of the links moving forward relative to the middle lugs or arms at the sides of the front follower block which bearing against the front abutments 7 on the cheek plates is stationary. When the springs have been compressed the strains not absorbed by them are transmitted to the channel beams at six separate points or places, inasmuch as simultaneously the ends of the key strike the forward ends of the seats, the ends of the middle slots in the links engage the middle lugs at the edges of the front follower block or plate, and the lugs 22 at the sides or edges 30 of the rear follower block come into contact with the abutments 10 at the front of the recess 12. In buffing, the draw bar, key, and front follower block move rearwardly, the links and rear follower block remaining stationary. When the springs have become compressed the remaining strains are transmitted to the channel beams or stringers at seven separate points or places, inasmuch as simultaneously the rear follower block rests 40 against the filler block and its edges engage the rear abutments 11, 11, the front follower block strikes the abutments 8, 8 at the rear of the recess 9, and the edges of the ends of the key are brought into contact 45 with the metal at the rear ends of the slots 5 at the front ends of the cheek plates. This distribution of the strains both in drawing and buffing after the springs have been compressed, prevents the breaking or 50 bending or other injury of any part or parts of the gear and thus the main end specified as the object of the invention is attained.

I have shown in Figs. 1 and 2 a relatively long front key passed through the draw bar, links, and cheek plates and webs of the supports, but there may be substituted therefor a relatively short key 100, such as shown by Fig. 7, which will be located entirely between the webs of the channel stringers.

60 What I claim is:

1. The combination in a draft gear, comprising sills, slotted links, a front follower, a rear follower, abutments for the followers, cushioning means between the followers, and a slotted draw bar, of a key passed

through the slots in the links and draw bar; and means connecting the rear ends of the links with the rear follower so the forward movement of the draw bar will move the rear follower; the front follower having its vertical side edges recessed for the passage of the links and within which recesses the links are located. 70

2. The combination in a draft and buffing gear, of supports with slots; abutments for followers, three abutments being located upon the face of each support; a front follower with its edges slotted located at the rear of the front abutments; a rear follower; cushioning means between the followers; a slotted draw bar; slotted draft links located within the slots in the edges of the front follower; means connecting the rear ends of the links with the rear follower; and a single key passed through the draw bar and links and movable within the slots of the supports; the movement of the rear follower in drawing being limited by the said intermediate abutments. 75

3. The combination in a draft and buffing gear, of supports with slots; cheek plates each with a vertically disposed abutment for a front follower; a front follower located at the rear of the abutments; abutments for a rear follower; a rear follower in front of said abutments; cushioning means between the followers; a slotted draw bar; slotted draft links; means connecting the rear ends of the links with the rear follower for advancing the rear follower in drawing; and a single key passed through the draw bar and links and movable within the slots of the supports; the ends of the said followers being slotted and said draft links being located within the slots of the followers each side of the cushioning means. 95

4. The combination in a draft and buffing gear, of supports with slots; cheek plates with abutments for a front follower; a front follower located at the rear of the abutments; abutments for a rear follower; a rear follower in front of said abutments; cushioning means between the followers; a slotted draw bar; slotted draft links; and a single key passed through the draw bar and links and movable within the slots of the supports; the said followers being slotted and also having lugs each integral with a follower located within the slots in the links; and the said links being located within the slots of the followers. 110 115

5. The combination in a draft and buffing gear, of supports; abutments for a front follower; a front follower located at the rear of the abutments; abutments for a rear follower; a rear follower having its edges slotted located in front of said abutments; cushioning means between the followers; a slotted draw bar; slotted draft links located within the slots of the rear follower; and a 120 125 130

single key passed through the draw bar and links; means being provided in connection with the rear follower and engaged by the links for advancing the rear follower in 5 drawing.

6. The combination in a draft and buffing gear, of supports; abutments for a front follower secured to the vertical surfaces of the supports; a front follower with its vertical edges slotted located at the rear of the abutments; abutments for a rear follower; a rear follower in front of said abutments; cushioning means between the followers; a slotted draw bar; slotted draft links; and 10 a single key passed through the draw bar and links; the said draft links being located within the slots in the front follower and engaging the rear follower.

7. The combination in a draft gear, of 20 metallic supports, spaced abutments riveted in the vertical surfaces of the supports, a front follower, a rear follower, cushioning means between the followers, a slotted draw bar, slotted draft links, a key within the 25 slots of the draw bar and ends of the links, means connecting the rear ends of the links with the rear follower, and means at the lower side edges of the followers for supporting the same; said rear follower being recessed and 30 the links being located within the recesses.

8. In a side link cushioned draft gear, 35 sills with inwardly projecting abutments, a follower with recesses at its opposite vertical edges located back of the said abutments, a slotted draw-bar in front of the follower, slotted draft links movably located within the recesses in the follower, and a key located within the slot in the draw- 40 bar and the slots in the links.

9. The combination of sills with inwardly projecting abutments; a rearwardly movable follower recessed at its vertical side edges located back of the abutments; cushioning

means back of the follower; means in connection with the sills for limiting the rearward movement of the cushioning means; a slotted draw bar; and slotted arms or links movably located within the recesses in the said follower, connected with the cushioning means at the rear of the follower, and also connected to the draw bar by a key which allows a rearward movement of the draw bar relative to said arms or links. 45

10. The combination in a draft gear, of 50 metallic supports, spaced abutments riveted to the vertical surfaces of the supports, a front follower, a rear follower, cushioning means between the followers, a slotted draw bar, slotted draft links, a key within the 55 slots of the draw bar and ends of the links, means connecting the rear ends of the links with the rear follower, and means for supporting said followers between said supports; said rear follower being recessed and 60 the links being located within the recesses. 65

11. The combination in a draft and buffing gear, of metallic supports, spaced abutments riveted to the vertical surfaces of the supports, a front follower, a rear follower, 70 cushioning means between the followers, a slotted draw bar, slotted draft links, a key within the slots of the draw bar and ends of the links, means consisting of lugs or arms at the sides of the rear follower projecting into the slots of the links and located entirely between the metallic supports for connecting the rear ends of the links with the follower, and means independent of the said lugs or arms for supporting the rear 75 follower and the rear ends of the links in line with the draw bar and rear abutment. 80

In testimony whereof I affix my signature in presence of two witnesses.

IRA O. WRIGHT.
